PHONOGRAPH PICK-UP CARTRIDGE

William A. Cavagnaro, Decatur, Ill., and Ronald K. Wiandt, Fort Jackson, S.C., assignors to General Electric Company, a corporation of New York

Filed Apr. 17, 1963, Ser. No. 74,495

Term of patent 14 years
(Cl. D26—14)

FIG.1

FIG.2

FIG.3

FIG.5

FIG.6

FIG.4

FIG. 1 is a top, front and right side perspective view of a phonograph pick-up cartridge, showing our new design;

FIG. 2 is a top view;

FIG. 3 is a left side elevational view;

FIG. 4 is a bottom view;

FIG. 5 is a front end elevational view; and

FIG. 6 is a rear end elevational view thereof.

We claim:

The ornamental design for a phonograph pick-up cartridge, as shown.
